UNITED STATES PATENT OFFICE.

GUNNAR C. ENGSTRAND, OF BROOKLYN, NEW YORK, ASSIGNOR, BY MESNE ASSIGNMENTS, TO SALVAGE PROCESS CORPORATION, OF NEW YORK, N. Y., A CORPORATION OF NEW YORK.

PUMPING APPARATUS.

Application filed March 18, 1924. Serial No. 700,069.

My invention relates to a pumping apparatus for the withdrawal of fuel oil and residue from the tanks of a vessel.

This liquid material is viscous, sticky, and in cold weather almost jelly-like, and due to its nature it cannot be pumped either in a solid column or in an aerated one, but it has to be transmitted in an air stream in a broken up condition.

10 My invention has for its object to furnish a steam ejector so as to divide the air transmission into two distinct lines viz. a low suction vacuum line which passes from the tank top into the ship tank and a low pressure discharge line which passes from the tank top over the ship side and discharges directly into a slop barge.

By raising the material by suction to the tank top only, the necessity of tanks and 20 high vacuum pumps is eliminated and an ordinary low suction steam ejector can be used.

25 My invention has also for its object to admit atmospheric air at the suction end in order to break up and carry the viscous material to the steam ejector.

30 My invention has also for an object to furnish several high velocity steam jets so as to still further accelerate and break up the viscous material so that the low pressure air stream which ensues after the condensation of the steam is able to carry the material over the ship side. In this way it is possible to use a pressure only slightly 35 higher than the atmospheric pressure to pump the viscous material through a hose of considerable length.

40 My invention has finally for its object to provide steam jets which are so constructed and located that the steam in emitting will strike the air and exchange its momentum to the air stream before it strikes the fluid material and condenses.

In the drawing:—

45 Fig. 1 shows the general pumping arrangement.

Figures 2 and 3 show the detail construction of the steam ejector.

50 Figures 4 and 5 show the detail construction of the suction nozzle.

Referring to the drawing in which like reference characters designate correspond-

ing parts, 1 represents the vessel from which the fuel oil is pumped. Alongside the vessel an ordinary slop barge 2 is moored.

55 A flexible hose is shown connecting the ship tank with the slop barge and this hose transmission line is divided into the low suction intake line 4 and the low pressure discharge line 5 by the steam ejector 3.

60 The steam ejector has three nozzles 6 which are of such a construction that they can be readily secured to standard fittings without obstructing the transmission line.

65 The nozzle 6 has a restricted opening 7 turned in the direction of flow through which opening the steam will emit at a velocity higher even than that of sound.

70 Single nozzles 6 are also furnished at regular intervals higher up the hose, their duty being to accelerate the air stream and to keep the viscous material from flowing together.

75 The steam is admitted to the nozzles 6 through the steam hoses 8 which are conveniently hooked up to the steam supply on board the ship.

80 An intake nozzle 9 with a reduced middle part 10 and an intake bell 11 to be inserted into the material to be pumped is supplied with the small holes 12 through which atmospheric air is admitted into the system.

85 Experiments have shown that a steam pressure of 75 lbs. per square inch will create a vacuum indicated by 20 inches on the mercury gauge at the suction end if no air is admitted thereto.

90 Experiments also show that a steam pressure six times as great as the discharge pressure is necessary for the working of the steam ejector.

95 Therefore in order to keep the steam pressure in the hoses within moderate and practical limits it is necessary to keep the discharge pressure of the ejector only slightly above the atmospheric pressure.

With a steam pressure in the ejector of 75 lbs. per square inch and with air admitted through six 5/16" openings into the suction nozzle the vacuum reaches 10 inches 100 at the intake and the inrush velocity of the air to the system is 600 feet per second.

This velocity is sufficient to break up the material which enters the system through the

restricted nozzle into fragments which the attenuated air stream in the suction line 4 carries to the steam ejector 3.

Here the fragments are still further broken up as steam emits from the nozzles 6 at a velocity in excess of 1000 feet per second.

It is a well recognized fact that the smaller the particles are the less the current required to carry the particles.

It has been found that a current velocity of 50 feet per second is sufficient to carry oily sludge and residue through a hose of 4 inches diameter when the material is heated

15 and broken up by a high velocity steam jet.

In order to maintain such a velocity through a 4" hose of considerable length without increasing the pressure beyond the capacity of the ejector it has been found imperative to furnish high velocity steam jets at intervals in the transmission line.

Each steam jet imparts to the residue carrying air current its heat as well as its momentum.

25 It is to be noted that the steam nozzles 7 are all provided with openings on the top side of the nozzle body, the lower side forming an efficient deflector for all the liquid particles which are contained in the air stream. In this manner the emitting steam will strike the air prior to the fluid material and the momentum exchange will take place prior to the condensation.

35 It is to be noted that the admitted air and not the admitted steam acts as the suspension medium.

This arrangement makes possible a great steam economy as a temperature considerably lower than that of steam may be maintained in the transmission line. Also the

employment of a low pressure air line insures the safety of the workman.

Referring to the intake nozzle its restricted construction prevents the material from filling the hose and thus seal the air inlets. 45

It is also readily understood that the more the suction bell is inserted in the material to be pumped the less will the head be against which the material is primarily lifted and thus by inserting the bell more or less into the material this head will be increased or decreased and the feed of material will be accordingly regulated. 50

I claim:—

1. A pumping apparatus having a tank 55 containing viscous material, a receiver at a higher level and a pipe line connecting them, comprising a nozzle having a restricted portion between the ends thereof and air admission apertures above said portion, said nozzle to be dipped into the material, and means in the line just above the tank to admit high velocity steam peripherally of the pipe in the direction of flow to draw in the air and material to drive it forward by the transfer of momentum and to break up the material into finer fragments. 60

2. A pumping apparatus including a tank, a pipe line having a nozzle dipping into viscous material in said tank and an ejector 70 providing a high velocity steam jet in the line just above the tank introducing steam in the direction of flow to draw in air and viscous material at said nozzle in fragments, to accelerate the flow of the stream as the steam contacts therewith, to break up the material into finer fragments as the same passes said jet, and to heat the material. 75
